FRANK NETSCHERT, OF NEW YORK, N. Y.

SITZ-BATH ATTACHMENT.

982,626.

Specification of Letters Patent. Patented Jan. 24, 1911.

Application filed May 26, 1908, Serial No. 435,171. Renewed June 24, 1910. Serial No. 568,719.

To all whom it may concern:

Be it known that I, FRANK NETSCHERT, a citizen of the United States, and a resident of the borough of Brooklyn, county of 5 Kings, city and State of New York, have invented a new and useful Improvement in Sitz-Bath Attachments for Bath-Tubs, of which the following is a full, clear, and exact description.

10 My invention relates to a sitz bath bowl and to means for attaching the same to bath tubs, and resides in the novel features of construction and in the combination of parts hereinafter described and particularly pointed out in the claims.

15 The object of my invention is to provide a sitz bath which may be quickly, securely, and easily attached to a bath tub, which may as readily be removed therefrom when not in 20 use, and which will take up but little room.

25 In the drawings, which show a preferred form of my invention, Figure 1 is an elevation, partly in section, of a bath tub, with my improved sitz bath attached thereto.

30 Fig. 2 is a perspective view of the frame or bracket used to support the sitz bowl over the tub. Fig. 3 is a plan view of the sitz bowl, *in situ*, with the part at the rear of the bath tub broken away, and Fig. 4 is a section on line 1—2 of Fig. 3.

35 The bowl, A, of my sitz bath may be of any suitable material and is, preferably, longer than it is broad. It consists of a relatively deep central basin, B, having a rim, C, flaring or curving outwardly and upwardly on the two sides so as to form fairly wide leg or thigh supports, D, D, for the bather, as will be hereinafter seen. At the 40 ends, E, E' the rim has merely the stiffening and finishing function common to all bowls and may, therefore, be quite narrow and of the usual rounded, flattened or other desired section.

45 To support the bowl over the bath tub, I employ a skeleton frame F, consisting of two similar metal rods each bent downward at one end to form a hook, G, adapted to slip over the front edge of the tub and, at a short distance from this hook, again bent downward, backward, and again upward, to form a depressed portion, H; each rod then continues straight back in a portion, I, which extends over the back of the tub. The two rods are joined by front and back pieces, J, J, of equal length, running parallel to the 50 length of the tub.

The bowl, A, is carried upon the horizontal segments, H, of the frame just described, the sloping portions, K, of the frame slipping into four notches, L, of the rim so as to steady the bowl and prevent its turning and the longer axis of the bowl being at right angles to that of the tub.

55 The frame, F, is preferably formed from round or square iron or steel bar, and may be of one piece only, the ends being welded or otherwise joined and the straight sections I, I, being sufficiently long to extend beyond the rear edge of the widest usual bath tub thus adapting the frame to any tub ordinarily to be met with. Or, the frame may be constructed in two sections held together by metal sleeves, M, in which the sections may be slid to or from one another so as to shorten or lengthen the frame, thus adapting 70 it for different widths of tubs, set screws, N, N, being used to lock the sections for any determined length of frame.

75 To use my improved sitz bath attachment, the frame and bowl being in position as shown in the drawings, and the bowl being filled with water, the bather seats himself over the bowl about midway of its two ends and facing forward with his legs hanging 80 over and outside of the front edge of the tub; his thighs will then be comfortably supported by the flaring lateral extensions, D, D. In this position the front and rear ends of the central basin, B, are not covered by the body and ready access is, therefore, had to the water both in front of and 85 behind the bather.

90 To enable the bather to take the midway seated position just described, naturally and without discomfort, the front rim, E, of the sitz bowl should be as narrow as possible as well as have its outer edge straight so that the basin B, may be brought as close as possible to the front of the bath tub. For this 95 same reason that portion of the frame, F, lying between the hooks, G, and the sloped portions, K, must be only just long enough to permit the sitz bowl to lie upon the frame without touching the inner side of the tub.

100 It is held by some authorities that the elimination of waste from the body is greatly aided by maintaining a seated position in very shallow water, say of a depth of two or three inches, either running or still. To adherents of this school, my improved sitz bath will be found very useful 105 and desirable as, given the above described

arrangement and posture the hips will be immersed to just about the mentioned depth.

Should it be desired to bathe in running water at a determined temperature, a small 5 rubber hose leading from the supply is laid into the rear end of the basin, B, the hot and cold water faucets adjusted so as to secure the desired mixture, and the water allowed to overflow at an opening, P, which is placed 10 in the front of the basin. When the bath is finished both the bowl and frame may be instantly removed and slipped away under the tub or in any other convenient location thus leaving the tub free for its ordinary and 15 usual purposes.

Having thus described my invention, I claim:

1. A sitz bath bowl longer than it is broad, and a skeleton frame adapted to removably support said bowl, said bowl being further provided with notches adapted to engage the frame and prevent movement of the bowl.

2. A sitz bath bowl longer than it is broad, a skeleton frame to removably support said bowl, a rim for said bowl of which the portions on each side of the longer axis are outwardly and upwardly flared so as to fit, and serve as a support for, the thighs of 25 a seated bather, and notches in the rim adapted to engage the frame so as to prevent movement of the bowl.

3. In a sitz bath attachment for bath tubs, a basin and a frame adapted to removably support said basin immediately adjacent to 35 the front edge of the bath tub, said frame comprising hooked portions adapted to engage said front edge so as to prevent rearward movement of the frame and rearwardly extending straight portions adapted to rest 40 upon the rear edge of the tub.

4. In a sitz bath attachment for bath tubs a basin having elevated outwardly extending thigh supports on each side and a straight 45 edged front portion, said basin being adapted to be removably supported immediately adjacent to the front edge of the bath tub by means of a frame comprising hooked portions adapted to engage said front edge, rearwardly extending straight portions adapted to rest upon the rear edge of the tub, and an intermediate depressed portion adapted to receive the basin proper; and notches in the rim of said basin adapted to engage the supporting frame and prevent 50 movement of the basin.

In testimony whereof I have hereunto set my hand in the presence of two subscribing witnesses this 25th day of May 1908.

FRANK NETSCHERT.
